UNITED STATES PATENT OFFICE.

GEORGE THOMAS FARRELL, OF COAHOMA, NORTH CAROLINA.

CASH-CARRIER.

SPECIFICATION forming part of Letters Patent No. 451,471, dated May 5, 1891.

Application filed November 6, 1890. Serial No. 370,521. (No model.)

To all whom it may concern:

Be it known that I, GEORGE THOMAS FARRELL, a citizen of the United States, residing at Coahoma, in the county of Lenoir and State 5 of North Carolina, have invented certain new and useful Improvements in Cash and Package Carriers; and I do declare the following to be a full, clear, and exact description of the invention, such as will enable others 10 skilled in the art to which it appertains to make and use the same.

This invention relates to an improvement in that class of store-service apparatus in which a fixed track or wire is used for a traveling car or cash-carrier; and the novelty will 15 be fully understood from the following description and claims when taken in connection with the accompanying drawings, in which—

20 Figure 1 is a side elevation of a section of my improved apparatus, showing a car in position upon the wire or track. Fig. 2 is a front view of the car, showing the track-wire in section. Fig. 3 is a perspective detail view 25 of the springs for starting the car and actuating the sliding notched block, showing the block in position to be engaged by an incoming car.

Referring by letter to said drawings, A indicates a hanger, which may be of any ordinary or approved construction, and is properly secured and braced to a ceiling in the usual manner. This hanger is provided at 30 its lower end or other suitable point with a 35 lug or arm *a*, which is designed to co-operate with the pull-cord in releasing the latch-bar from the sliding notched block, as will be presently explained.

B indicates a track-wire. One end is shown 40 secured to the hanger, the opposite end of said track being similarly secured to a corresponding hanger at the desired point of destination.

C indicates the car designed to carry cash 45 or packages. This car may be of the usual construction, having the removable receptacle D, which may be secured to the main frame of the car by a bayonet-slot fastening or other suitable means, and the frame carries the 50 usual traction-wheels *b*, journaled in hangers, so that the car may be properly suspended

from the track-wire B and allowed to move freely thereon.

At the opposite ends of the car is pivoted a catch E, which is designed to engage a sliding notched block or hook on the track-wire B. These catches E are preferably of an angular form, so as to have the shouldered or catch portion normally in a horizontal plane and the opposite branch in a vertical plane, 60 as shown at *d*, so that it may encounter the arm or lug *a* of the hanger. The catches E are backed by springs *e* in such a manner as to hold the catch portion or branch in a position as to engage with the sliding notched 65 block or hook on the track and to allow the catch to disengage itself from said hook or block when the depending branch of the catch strikes the lug or arm of the hanger.

Attached to one side of the hanger A at 70 about the same plane as the wire track B is one end of a flat spring F, which is curved outwardly, and thence inwardly and forwardly, and may have the notched block or hook H formed integral therewith or made 75 separately and fixed to the outer end thereof.

I indicates a pull-cord. This cord passes over a pulley *i* in the hanger A and is attached at its opposite end to the sliding block or hook H, which is notched in its under side and is 80 provided with a hole to receive the wire track B, whereby said block may slide thereon.

The propelling-spring G, which is of a similar form to the spring F, and has one end secured to the opposite side of the hanger, is 85 curved outwardly, and thence inwardly and forwardly, so as to overlap the wire B in advance of the slide-block H and in a position to bear against one of the angular ends L of the car-frame.

Although I have described the car-propelling and sliding-block-actuating springs as formed separately, yet it is obvious that they might be formed of a single piece of material and secured at a suitable point to the 95 hanger.

In operation it will be seen that as the car moves forcibly in the direction of one of the hangers the pivoted catch on one end of the car-frame will engage with the notched block 100 H on the track, when said car will be held in such position until it is desirable to return it

to the desired destination. To propel the car the operator should take hold of the pull-cord 1 and draw the same until the depending branch *d* of the pivoted catch strikes the arm 5 *a* of the hanger. In this position the springs F and G, having been bowed, as the catch is removed from the notched block II the spring G will come into action and propel the car with its full force along the track-wire, while 10 the spring F will return the slide-block or hook to the position shown in Fig. 1, and ready to engage the car again.

Having described my invention, what I claim, and desire to secure by Letters Patent, 15 is—

In a cash and package carrier, the combination, with the hanger A, having the hori-

zontal branch *a* at its lower end, of the wire track, the spring F, secured at one end to the hanger and curved outwardly and thence inwardly and carrying the notched block II, the spring G, secured at one end to the hanger and at its opposite end overlapping the wire and arranged in advance of said sliding notched block, a pull-cord attached to the said sliding block, and a car movable on the wire and having the pivoted angular catches E, provided with springs *e*, substantially as specified.

In testimony whereof I affix my signature in presence of two witnesses.

GEORGE THOMAS FARNELL.
